United States Patent Office

Des. 210,329
Patented Feb. 27, 1968

210,329

REFLECTING TRAFFIC GUIDE OR SIMILAR ARTICLE

John B. Keats, Marietta, Ohio, assignor to Borg-Warner Corporation, Chicago, Ill., a corporation of Illinois

Filed May 31, 1966, Ser. No. 2,470

Term of patent 14 years

(Cl. D72—1)

FIG. 1

FIG. 2

FIG. 3

FIGURE 1 is a top plan view of a reflecting traffic guide or similar article showing my new design;

FIGURE 2 is a front elevation thereof; and

FIGURE 3 is a side elevation thereof.

I claim:

The ornamental design for a reflecting traffic guide or similar article, substantially as shown.
